COMBINED GOLF TEE HOLDER AND TEES

Edward L. Cicero, 52-62 66th St.,
Maspeth, N.Y. 11378

Filed Nov. 30, 1971, Ser. No. 203,513

Term of patent 14 years

Int. Cl. D21—02
U.S. Cl. D34—5 GT

FIG 1

FIG 2

FIG 3

FIG 4

FIG 5

FIG. 1 is a top plan view of a combined golf tee holder and tees, the bottom plan view being substantially similar. FIG. 2 is a view in side elevation.

FIG. 3 is an end view.

FIG. 4 is a top plan view similar to FIG. 1 with tees removed for convenience of illustrating the holder.

FIG. 5 is a top plan view similar to FIG. 4 illustrating an alternate form of hole pattern.

I claim:

The ornamental design for a combined golf tee holder and tees, as shown and described.
